HAIR WAVER.

Application filed November 2, 1927. Serial No. 230,651.

Our invention relates to a hair waver of a character to adapt it for individual use by those requiring waving of the hair, and capable of producing Marcel waves.

5 The general object of our invention is to provide a hair waver of the indicated character of simple construction and characterized by convenience of assembly, operation and control, as well as to provide a hair 10 waver so constructed as not to strain or injure the hair being waved.

Reference is to be had to the accompanying drawings forming part of this specification, it being understood that the drawings 15 are merely illustrative of examples of the invention.

Figure 1 is a plan view of a hair waver embodying our invention;

Figures 2 and 3 are respectively transverse 20 and vertical sections as indicated by the lines 2—2 and 3—3 in Figure 4;

Figure 4 is a longitudinal vertical section;

Figure 5 is a longitudinal vertical section 25 showing the cover raised and the clamps in open position to conveniently receive the hair to be waved;

Figure 6 is a diagrammatic plan view indicating the manner of placing the hair in the hair waver;

30 Figure 7 is a fragmentary view in transverse vertical section indicating the hair when placed in the hair waver as in Figure 6;

Figure 8 is a view similar to Figure 6 35 but showing the condition of the hair after having been moved by relative movements of the clamping means to give the hair a waved form;

Figure 9 is a detailed transverse vertical 40 section showing the parts illustrated in Figure 8 after the movement of the hair into waved form; and

Figure 10 is a detailed vertical section 45 showing one end of the waver in modified form.

In carrying out our invention in accordance with the illustrated examples, and referring at first more particularly to Figures 1 to 9, a box-like body 10 is provided 50 open at the top and formed at the sides with lateral flanges 11 with pads 12 thereon to contact with the head of the person. A cover 13 is hinged at one end to the body 10, as at 110. One or more longitudinal

partitions 14 are provided according to the 55 size of the hair waver, two being shown in the present instance to form three compartments. The numeral 15 indicates the sides of the body 10. On the cover 13 at the under side are downwardly bent flanges 16 60 having pads 17 of felt or other soft material to close down against the upper edges of the partitions 14 and sides 15 to clamp a strand of hair. Catch hooks 18 are formed at the upper edges of the partitions 14, and 65 a turnable latch 19 having a knob 20 is adapted to engage with said catches, which latter project through openings 119 in cover 13. The cover 13 has eight openings 113 for the examination of the condition of the 70 hair being waved, said openings being closed by a lift cover 21 hinged as at 22 to cover 13. At the opposite end from the hinge is a catch 23 turnable by a knob 24 to engage beneath the top of cover 13 at one end of 75 openings 113.

In addition to the side hair clamps 16 carrying the pads 17 and cover 13 formed with end flanges 213 at the openings 113, a plurality of clamps are provided as follows: 80 In each compartment confined by the sides 15 and the partition 14 a bottom clamp 25 is provided, and a top clamp 26 having an electrical heating element 27 therein, the the cords 28 leading to which element 85 pass through a nipple 29 at the bottom of the body 10. The said clamps are concavo-convex. The bottom clamp 25 is hingedly connected with the body 10 by a broad link 30 connected at one end with said bottom 90 clamp 25 and pivotally hung on transverse rod 31, passing through the partitions 14 and sides 15. Each upper clamp element 26 at its front end is hinged by a link 32 to transverse rod 33 on the cover 13. At the 95 opposite end the upper and lower clamps 25, 26 are hinged to each other by a common hinge member, as at 34, and a link 35 connects both upper and lower clamps at the hinge 34 with transverse rod 36 on body 10. 100 The arrangement permits the two concavo-convex clamp elements 25, 26 to have a swinging movement with the rods 31, 33 and 36 as pivotal centers. To impart a swinging parallel movement to the clamps 25, 26 suitable hand operated means is provided, there being shown links 37 pivoted within the body 10 to the lower clamp element 25, as at 38,

the opposite end of each link 37 being above a slot 39 in the bottom of the body 10 and provided with an operating finger piece 40.

In the use of the above described hair waver a strand of hair, indicated at A in Figures 6 to 8, is waved by laying the strand across the partitions 14 and sides 15, as in Figure 6, the cover 13 being then in raised position. The cover 13 is then closed down thus disposing the clamp sections 25, 26 in association with each other and with the hair therebetween, as indicated in Figure 7. In order to give the wavy form to the bent strand A, as shown in Figure 8, each pair of clamp sections, composed of the lower clamp section 25 and upper clamp section 26, is swung longitudinally by its link 37 and finger hold 40, it being understood that in the illustrated example showing three pairs of clamps the center one is moved in the opposite direction from the side clamps 25, 26. The hair is not unduly strained because as one pair of clamp sections 25, 26 move upwardly in one direction, the adjacent pair of clamps move in an opposite direction, each pair of clamp sections rising from the position of Figure 7 to the position of Figure 8, the hair not being immovably held, however, at any one of the moving points, that is, at the upper edges of the partitions 14 or equivalent elements or by the clamp sections 25, 26. Thus, undue strain on the hair is prevented because it is permitted to slide at these clamping points. The hair is thus bent downwardly over the partitions 14 and sides 15, and there is also imparted a forward and back movement of the strand of hair to complete the waving operation.

Referring to Figure 10, illustrating a modified form, the parts are the same in the main as in the first described construction, the only difference being that in the sides 15 of the body 10 and partitions 114 there are arcuate slots 53 in which guide pins 54 have movement, said slots 53 being reversed at the opposite ends of adjacent partitions 114 giving the reverse movement of adjacent pairs of clamp sections 25, 26.

We would state furthermore that while the illustrated examples constitute practical embodiments of our invention, we do not limit ourselves strictly to the exact details herein illustrated, since, manifestly, the same can be considerably varied without departure from the spirit of the invention as defined in the appended claims.

We claim:

1. A hair waver including a body, a cover

for said body, a clamp swingably connected at one end to a member on the body, a co-operating clamp section swingably connected with the cover at that end corresponding with said swingably connected first mentioned clamp, and a link pivotally connected at one end with the body and swingably connected to both clamps at the end opposite the first mentioned ends of said clamps, together with heating means associated with the second mentioned clamp element to partake of the movement thereof.

2. A hair waver including a body, longitudinal elements on said body, pairs of clamps swingably mounted at opposite sides of said elements, and manually controlled means optionally operable to move said pairs of clamps in opposite directions.

3. A hair waver including a body, a cover hinged at one end to said body, a clamp swingably mounted at one end on the body, a pair of clamps swingably mounted at one end on the cover at the same end as the first mentioned end of the first clamp section, so that the second mentioned clamp section will be raised and lowered with the raising and lowering of the cover, and means swingably mounting the opposite ends of said clamps.

4. A hair waver including a body, longitudinal elements in said body, a cover hinged at one end to the body, means on said cover to co-act with said longitudinal elements and with the sides of the body to clamp a strand of hair thereon, and manually controlled means optionally operable to cause movement of the strand of hair in opposite directions.

5. A hair waver including a body, a cover for said body, a clamp swingably connected at one end to a member on the body, a co-operating clamp section swingably connected with the cover at that end corresponding with said swingably connected first mentioned clamp, and a link pivotally connected at one end with the body and swingably connected to both clamps at the end opposite the first mentioned ends of said clamps.

6. A hair waver including means to clamp a strand of hair at separated points, and movable clamping means for the hair between said separated points, the said clamping means at all the points of clamping permitting the slipping of the hair to prevent undue strains thereon.

WILLIAM J. PERKINS.
EMMA HAGEMEISTER.
